LAPPING MACHINE

Herbert S. Indge, Westboro, Mass., assignor to
Norton Company, Worcester, Mass., a corpora-
tion of Massachusetts

Application September 15, 1939, Serial No. 295,093

10 Claims. (Cl. 51—118)

The invention relates to lapping machines; and more particularly to a lapping machine for simultaneously lapping the opposed faces of a flat work piece.

One object of the invention is to provide a simple and thoroughly practical lapping machine for producing surfaces of extremely high quality. Another object of the invention is to provide a lapping machine having two opposed lapping elements which are arranged so that a substantially uniform surface speed of the lapping element may be obtained throughout the entire surface of the lapping element. Another object of the invention is to provide a lapping machine of the opposed lapping element type in which each lapping element is composed of a plurality of concentric rotatable lapping elements each of which is independently rotated. Another object of the invention is to provide a lapping machine with two opposed lapping elements each of which comprises a plurality of concentric rotatable lapping wheels together with an independent driving mechanism for each of said concentric wheels which is arranged so that a substantially uniform surface speed may be obtained throughout the entire extent of each of said lapping elements. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a vertical sectional view through the improved lapping machine, showing the arrangement of the opposed lapping elements together with the driving mechanism therefor;

Fig. 2 is a fragmentary plan view showing the mechanism for raising and lowering the upper lapping elements;

Fig. 3 is a fragmentary sectional view taken approximately on the line 3—3 of Fig. 1, showing the driving mechanism for the work carrying cage; and

Fig. 4 is a plan view of the lower lapping element.

The improved lapping machine has been illustrated in the drawings, comprising a base 10 which supports a vertically extending column 11.

The base 10 and the column 11 serve as supports for two opposed lapping elements. The base 10

is provided with a vertically extending sleeve 12 which rotatably supports a sleeve 13. The upper end of the sleeve 13 is provided with a driving plate 14 which supports an annular lapping ring 15 having an upper plane lapping surface for abrading the work piece. The lower lapping element is preferably composed of a plurality of independently rotated lapping members all of which are provided with plane faces which are aligned to present a common plane lapping surface for abrading the under surface of the work piece to be lapped.

A rotatable sleeve 16 is supported within the sleeve 13 and is provided at its upper end with a driving plate 17 which serves as a support for a ring-shaped lapping wheel 18. In order to produce a break-up motion, thus breaking up the abrading lines produced by a plurality of concentric lapping elements, the lapping ring 18 is preferably provided with an inner aperture which is eccentric with its axis of rotation. The sleeve 16 is provided with a pair of eccentrically mounted bearings 19 and 20 which serve to support a vertical rotatable spindle 21 and are arranged to support the spindle 21 with its axis eccentric to the axis of the rotatable sleeve 16. The upper end of the spindle 21 is provided with a driving plate 22 which supports an annular lapping ring 23 having an upper plane lapping surface. The three concentric lapping wheels 15, 18 and 23 are so arranged and mounted that their upper plane operative faces are aligned to coincide in a common plane to produce a lower plane lapping surface.

Due to the eccentric mounting of the spindle 21, when the spindle is rotated and its supporting sleeve 16 is rotated, the lapping element 23 is moved not only in a rotary but also in a planetary path, thus producing a relative transverse movement between the operative portions of the abrading surface, and thereby producing a break-up motion so as to eliminate the formation of scratches or markings on the work surface.

In order to obtain a uniform lapping operation upon the surface of the work piece, it is desirable to provide a substantially uniform surface speed at the inner and outer portions of the lapping surface. In order to attain such a uniform surface speed of the lapping surface, the three concentric lapping wheels 15, 18 and 23 are preferably rotated at different speeds so that their surfaces travel at a substantially uniform surface speed.

The base 10 is provided with a driving mechanism comprising an electric motor 30 which is

provided with a V-grooved driving pulley 31. The driving pulley 31 is connected by means of a V-belt 32 with a V-grooved pulley 33 which drives a worm 34. The worm 34 meshes with a worm gear 35 which is keyed to a rotatable shaft 36. The shaft 36 is rotatably supported in a bearing 37 which is fixedly mounted within the machine base 10 and a bearing 38 which is fixedly supported on the column 11. The worm 34 also meshes with a worm gear 39 which is keyed to a rotatable shaft 40. The shaft 40 is rotatably journalled in a bearing 41 fixedly mounted within the base 10 and a bearing 42 which is fixedly mounted at the upper portion of the column 11.

The lower end of the shaft 36 is provided with a V-groove pulley 45 which is connected by a V-belt 46 with a V-grooved pulley 47 which is keyed to the lower end of the sleeve 13, whereby a rotary motion may be transmitted through the sleeve 13 to rotate the lapping wheel 15. The shaft 36 also supports at its lower end a larger diameter V-groove pulley 48 which is connected by means of a V-belt 49 with a V-grooved pulley 50 which is fixedly keyed to the lower end of the spindle 21. A pivotally mounted idler pulley 51 is provided to tension the belt 49 during the planetary movement of the lapping wheel spindle 21.

The lower end of the shaft 40 is provided with a V-groove pulley 53 which is connected by means of a V-belt 54 with a pulley 55 which is fixedly keyed to the lower end of the rotatable sleeve 16 to impart a rotary motion to the lapping wheel 18. In the preferred construction it is desirable to increase the lapping and break-up motion by rotating the intermediate lapping wheel 18 in the opposite direction from the lapping wheels 15 and 23. The lapping and break-up motion is further increased by imparting a rotary and planetary movement to the wheel 23. This is preferably accomplished, as illustrated, by the worm and worm gear drive which is arranged to rotate the shaft 36 and the shaft 40 in opposite directions.

An upper opposed lapping element is provided to simultaneously engage and lap the upper surface of the work piece. The column 11 is provided with a cylindrically shaped aperture 60 which serves as a support for a post or column 61 having a horizontally extending arm 62 which serves as a rotatable support for a sleeve 63. The sleeve 63 supports a driving plate 64 at its lower end which in turn carries a ring-shaped lapping element 65. The sleeve 63 in turn serves as a rotatable support for a sleeve 66. The sleeve 66 is provided at its lower end with a driving plate 67 which supports a ring-shaped lapping element 68. The ring-shaped lapping element 68 is preferably formed with its inner aperture eccentric to its axis of rotation to facilitate the rotary and planetary movement of an inner wheel to be hereinafter described. The sleeve 66 serves as a support for a pair of spaced bearings 69 and 70. The bearings 69 and 70 rotatably support a vertical spindle 71 which supports a driving plate 72 at its lower end. The plate 72 serves as a support for a ring-shaped lapping element 73. The three upper lapping elements 65, 68 and 73 are all arranged with plane lapping surfaces which are positioned to form a common plane lapping surface to cooperate with the lower lapping elements to simultaneously lap the opposed faces of a plurality of flat work pieces.

The shafts 36 and 40 serve not only as driving

mediums for the lower lapping elements but also are drivingly connected to rotate the upper lapping elements. The shaft 36 is provided at its upper end with a pulley 75 which is connected by means of a belt 76 with a pulley 77 which is fixedly keyed to the upper end of the rotatable sleeve 66 to transmit a rotary movement to the lapping element 68. The shaft 40 is provided adjacent to its upper end with a pulley 78 which is connected by means of a belt 79 with a pulley 80 which is fixedly keyed to rotate the sleeve 63 and the lapping wheel 65 supported thereby.

The shaft 40 also supports at its upper end a pulley 81 which is connected by means of a belt 82 with a pulley 83 which is fixedly mounted on the upper end of the spindle 71 which supports the lapping wheel 73. A pivotally mounted rotatable idler pulley 84 is provided to tension the driving belt 82 during the rotary and planetary movement of the lapping wheel spindle 71.

To facilitate loading of work pieces into the machine, the upper lapping wheels 65, 68 and 73 together with their supporting mechanisms are arranged to be moved toward and from the lower lapping element. The pulleys 75, 78 and 81 are preferably formed as wide faced pulleys to enable a continuous drive being imparted to the upper lapping wheels during the approaching and receding movement of the same. The vertically movable column 61 is provided with a rack bar 90. To facilitate a vertical movement of the column 61, a manually operable mechanism is provided comprising a hand wheel 91 which is mounted on the end of a rotatable shaft 92. The inner end of the shaft 92 is provided with a bevel gear 93 which meshes with a bevel gear 94 supported on one end of a rotatable shaft 85 which is journalled in suitable bearings in the column 11. The shaft 85 also supports a worm 86 which meshes with worm gear 87. The worm gear 87 is mounted on one end of a rotatable shaft 95. The shaft 95 carries a gear 96 which meshes with the rack bar 90. It will thus be readily apparent that a rotary movement of the manually operable wheel 91 serves through the rack and gear mechanism above described to move the column 61 and the upper lapping wheels together with their driving mechanism supported thereby vertically toward or from the lower lapping element to facilitate removal of finish ground work pieces and the insertion of new work pieces to be lapped.

A work carrying cage 100 is provided having a plurality of work receiving apertures 101 to support a plurality of work pieces between the opposed lapping elements, whereby the opposed faces of the work piece may be simultaneously lapped to a predetermined extent. The cage 100 is given a combined rotating and gyrating movement, so that the work pieces are carried in an irregular path between the opposed lapping elements. The periphery of the cage 100 is formed as a spur gear which meshes with three symmetrically arranged gears 104, 105 and 106. Each of the gears 104, 105 and 106 is keyed to a pin 107, 108 and 109, respectively. The pins 107, 108 and 109 are mounted eccentrically on the upper surface of a rotatable plate 110 (only one of which has been shown in Fig. 1). The plate 110 extends beyond the periphery of the gear 104 and serves as a support for the cage 100 so that the cage rests on the three spaced plates 110, preferably out of engagement with the lower lapping element. The plates 110 are mounted on the upper end of a rotatable shaft

111 which is journaled in a bearing 112 formed in a portion of the frame which is fixedly mounted relative to the base 10.

In order to drive the cage 100, an electric motor 115 is mounted within the base 10. The motor 115 is provided with a motor shaft 116 which supports a sprocket 117 at its outer end. The sprocket 117 is connected by means of a driving chain 118 with a sprocket 119 mounted on a rotatable shaft 120. The inner end of the shaft 120 is provided with a bevelled gear 121 which meshes with a bevelled gear 122 which is mounted on the lower end of the shaft 111. Each of the shafts 111 is arranged so that it may be synchronously rotated so that the gears 104, 105 and 106 continuously mesh with the gear teeth 102 formed in the periphery of the cage 100. In order to synchronously drive all of the gears 104, the shaft 111 is provided with a gear 123 which meshes with a large internal rotatable gear ring 125 which is rotatably supported in a bearing surface 124 formed in a frame fixed to the base 10. Each of the shafts 111 supporting the gears 104, 105 and 106 is provided at its lower end with gears 123 which mesh with the internal rotatable ring gear 125. It will be apparent from the foregoing disclosure that when the shaft 120 is rotated to rotate the vertical shaft 111 supporting the gear 104, a corresponding rotary and gyrating movement will be imparted to the gears 105 and 106, respectively, by means of the gear 123 and the rotatable internal ring gear 125. Due to the rotary and gyrating movement of the gears 104, 105 and 106, the work supporting cage 100 will be given a combined rotary and planetary movement to carry the work pieces supported thereby through an irregular path between the opposed lapping elements above described.

The operation of this improved lapping machine will be readily apparent from the foregoing disclosure. Assuming the parts to be in the position illustrated in Fig. 1, a plurality of work pieces are placed in the plurality of apertures 101 in the cage 100, and the motors 30 and 115 are then started to rotate and gyrate the cage 100 and to impart a rotary movement to the lower lapping wheels 15, 18 and 23 and also to the upper lapping wheels 65, 68 and 73. The manually operable wheel 91 is then rotated to lower the column 61 and the head 62 to move the upper lapping elements composed of the lapping wheels 65, 68 and 73 into operative lapping engagement with the work pieces. The lapping operation may then be continued to lap the opposed faces of the work piece to the desired extent so as to produce a highly refined lap surface thereon. After a lapping operation has been completed, the manually operable wheel 91 is rotated to again raise the column 61, the head 62 and the upper lapping elements comprising the lapping wheels 65, 68 and 73 to an upper inoperative position to facilitate removal of the lapped pieces of work and insertion of new work pieces thereinstead.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the 75

accompanying drawings is to be interpreted as illustrative and not in a limiting sense.

I claim:

1. In a lapping machine, a pair of opposed lapping elements, each of said lapping elements comprising a plurality of concentric independently rotated lapping wheels, means independently to rotate each of said wheels, a work supporting cage between said elements having a plurality of work receiving apertures formed therein, means to impart a planetary movement to at least one of said lapping wheels, and a driving mechanism for said cage to rotate and gyrate said cage to carry a plurality of work pieces through an irregular path between the operative faces of said lapping elements.

2. In a lapping machine, a pair of opposed lapping elements each having a substantially plane operative face, each of said lapping elements comprising a plurality of concentric rotatable lapping wheels, means independently to rotate each of said wheels at different speeds whereby a substantially uniform surface speed may be obtained throughout the extent of the operative face of each of said lapping elements, means to impart a planetary movement to at least one of said lapping wheels of each element, a work cage between said elements having a plurality of work receiving apertures therein, and means to rotate and gyrate said cage simultaneously to carry a plurality of work pieces through an irregular path between the operative faces of said lapping elements.

3. In a lapping machine, a pair of opposed lapping elements each having a substantially plane operative face, each of said lapping elements comprising three substantially concentric rotatable lapping wheels, means to rotate the outer and inner wheels of each element in the same direction, means to rotate the intermediate wheel of each element in the opposite direction therefrom, and means to impart a planetary movement to the inner wheel of each element.

4. In a lapping machine, a pair of opposed lapping elements each having a substantially plane operative face, each of said elements comprising three substantially concentric rotatable lapping wheels, means to rotate the outer and inner wheels of each element in the same direction, means to rotate the intermediate wheel of each element in the opposite direction from the adjacent outer and inner wheels, and means to impart a planetary movement to the inner wheel of each element, said opposed lapping elements having their respective wheels rotating in opposite directions.

5. In a lapping machine, a pair of opposed lapping elements each having a substantially plane operative face, each of said lapping elements comprising a plurality of concentric rotatable lapping wheels, means independently to rotate each of said wheels, and means to impart a planetary movement to at least one of the wheels of each lapping element.

6. In a lapping machine, a pair of opposed rotatable lapping elements each having a substantially plane operative face, a work carrying cage having a plurality of work receiving apertures located between said elements, means to impart a rotary and gyrating movement to said cage, one of said elements at least comprising a plurality of concentric rotatable lapping wheels, means independently to rotate each of said wheels, and means to impart a planetary movement to at least one of said wheels.

7. In a lapping machine, a pair of opposed lap-

ping elements each having a substantially plane operative face, each of said lapping elements comprising three substantially concentric rotatable lapping wheels, means to rotate the outer and inner wheels of each element in the same direction, means to rotate the intermediate wheel of each element in the opposite direction therefrom, means to impart a planetary movement to the inner wheel of each element, a work cage between said elements having a plurality of work receiving apertures therein, and a driving mechanism for said cage to rotate and gyrate said cage simultaneously to carry a plurality of work pieces through an irregular path between the operative faces of said lapping elements.

8. In a lapping machine, a pair of opposed lapping elements each having a substantially plane operative face, at least one of said lapping elements comprising a plurality of substantially concentric rotatable lapping wheels, means inde-

pendently to rotate all of said lapping wheels, and means to impart a planetary movement to at least one of said lapping wheels.

9. In a lapping machine, a pair of opposed lapping elements each having a substantially plane operative face, at least one of said elements comprising a plurality of substantially concentric rotatable lapping wheels, means independently to rotate all of said lapping wheels, and means to impart a planetary movement to the inner lapping wheel.

10. In a lapping machine, a pair of opposed lapping elements each having a substantially plane operative face, each of said lapping elements comprising a plurality of substantially concentric rotatable lapping wheels, means independently to rotate all of said lapping wheels, and means to impart a planetary movement to at least one of the lapping wheels of each element.

HERBERT S. INDGE.
